KARL WITTIG, OF ZELL, GERMANY.

COMPRESSED-AIR ENGINE.

Application filed October 9, 1925, Serial No. 61,529, and in Germany October 22, 1924.

The invention relates to compressed air motors, that is driver engines to drive other apparatus, particularly in mines, where it is usual to employ compressed and therefore heated air furnished by a compressor to drive the subterraneous apparatus. It is more particularly applicable to air motors of the type comprising radial blades or vanes adapted to rotate within a substantially crescent shaped working chamber.

In connection with compressed air engines of such kind which are used in mining operations, it is necessary to prevent the extensive cooling effect of the compressed air upon expanding on the exhaust side of the engine from freezing water vapour contained in the exhaust air and thus restricting or choking up the exhaust passage, as this disadvantage prevents the complete consumption of the compressed air by expansion. The provision of water separators for previously withdrawing from the air the water vapour contained therein has proved to be uneconomical and uncertain, while other suggestions such, for instance, as the provision by means of special separate auxiliary compressors for supplying heat, appear to be unpracticable and intricate.

The object of the present invention is to prevent, without providing any separate machines or devices, the formation of ice in the exhaust passages while at the same time, obtaining a much greater expansion in the engine than was previously possible. By the employment of a device, which in no way necessitates any great alteration in the construction of the usual type of compressed air engine, no considerable expenditure is incurred.

According to the invention, this object is attained by causing the warm working compressed air of admission such as it is furnished by a compressor, or a portion thereof, to flow round the exhaust side of the engine casing before reaching the actual working portion of the engine, so as to heat in some respect the exhaust part of the engine casing and to prevent freezing of water vapour within the exhaust opening, which otherwise would take place on account of the extensive expansion of the air on the exhaust side, a portion of the exhaust air being also arranged to be again compressed within the engine and reintroduced into the

working portion thereof after previously delivering its heat of compression to the casing and rotor.

The invention will now be described by way of example with reference to the accompanying drawing illustrating a compressed air engine having rotating vanes and a working space of substantially crescent shaped cross section;

Figure 1 being a vertical sectional view, and Figure 2 a horizontal sectional view thereof, illustrating the arrangement of the heating sleeve or jacket around the motor casing.

Referring now to the drawing it will be seen that a rotor *r* having radially movable vanes *s* is arranged eccentrically to the casing *A*, thus forming a working space of substantially crescent shaped cross section between the periphery of the rotor and the casing. The inlet chamber of the engine is indicated at *b*, the inlet port below the rotor at *f* and the exhaust chamber situated on the side of the rotor opposite to the inlet chamber is indicated at *c*.

The casing *A* is provided with a hollow sleeve or jacket *a* extending for the most part around the exhaust side of the casing, a conduit *d* for supplying the working compressed air to the engine being connected to this sleeve or jacket the outlet of which on the other hand is connected by means of a pipe *e* or directly to the inlet chamber *b* of the engine. The hot or heated air, after it has given off a part of its heat in the jacket *a* to the walls of the casing *A*, flows through the port *f* into the compartments formed between the vanes *s* of the rotor *r*, which is thereby rotated in the direction of the arrow (Figure 1) and during the process of expansion flows into the exhaust chamber *c*.

The object of these arrangements is to use compressed air admitted generally at a temperature of 20° to 50° C. to first flow around the exhaust side of the engine and to thus keep same at a temperature which does not allow freezing of water vapour contained in the air, the heat thus transferred to the exhaust part of the engine casing thus compensating to a great extent the cooling effect which is due to the extensive expansion of the working air at its exhaust and otherwise would cause freezing of the water vapour. This prevents to a great

extent the danger of ice forming and adhering in the exhaust passage of the engine, thus avoiding restricting or choking up of this passage, as would be the case in mine 5 compressed air motors that have no protective arrangements of such kind.

In order to ensure that the heating action is efficiently carried out, according to the invention the engine itself is so arranged as 10 to operate partly as a compressor. In Figure 1 an inner cylindrical wall is indicated at *v* which covers the working space on the inlet side, a similar wall *u* being provided near to the exhaust chamber *c* adjacent the 15 sleeve or jacket *a*, and constitutes as does *v* a part of the body of the casing.

Inasmuch as the rotor compartments as they pass the wall *u* are cut off from the exhaust chamber *c* a remaining portion of 20 the cold expanded exhaust air is here compressed again. This spontaneously heated compressed air is continuously supplied to the inlet port *f* but gives off a considerable portion of its heat previously to the casing, 25 the rotor and particularly to the wall *u*. In this manner by reason of the supply of hot air to the engine through the jacket *a* and of the heat produced by the auxiliary compression, the casing and particularly the part 30 surrounding the exhaust, is kept warm in all circumstances, thus preventing the freezing of the water vapour at the exhaust side of the engine.

The invention thus consists in utilizing 35 the hot or previously heated working compressed air to heat the casing on the one hand, and on the other hand causing the engine itself to act as a compressor so that by compressing a portion of the expanded

air additional heat is generated which is 40 conducted to the casing of the engine.

The invention is evidently not limited to the particular construction and arrangement of parts herein described but various modifications may be made therein without exceeding the scope of the invention. For instance, instead of causing the whole of the working compressed air to flow through the jacket *a* a portion of this air may be diverted and conveyed to the neighbourhood of the 45 50 exhaust for heating purposes.

What I claim is:

A compressed air motor of the kind described, comprising a casing, an admission and an exhaust port thereon, a compressed 55 air jacket on said casing extending up to said exhaust port, means to supply said jacket with compressed air preliminarily to the use thereof for working, a rotor eccentrically mounted in said casing, radially movable vanes on said rotor, said casing having two wall parts between said ports to form with the rotor, the one, a crescent shaped compressed air expansion chamber 60 for the operation of compressed air upon the rotor vanes, the other, a crescent shaped exhaust air compressing chamber between the exhaust and the admission ports of the casing for taking in and compressing a portion of the exhaust air, and connecting 65 70 means between said jacket and the admission port for admitting the compressed air for working, substantially as and for the purpose described.

In witness whereof I have hereunto signed 75 my name this 28th day of September, 1925.

KARL WITTIG.
